SIGNORS TO MILLERS FALLS COMPANY, OF MILLERS FALLS, MASSACHUSETTS, A
CORPORATION OF MASSACHUSETTS.

AUTOMATIC TOOL FOR BORING.

942,572.

Specification of Letters Patent.

Patented Dec. 7, 1909.

Application filed December 22, 1908. Serial No. 468,774.

To all whom it may concern:

Be it known that we, JOHN A. LELAND and WILLIAM G. STEBBINS, both of Montague, in the county of Franklin and State 5 of Massachusetts, have invented certain new and useful Improvements in Automatic Tools for Boring, &c., of which the following is a specification.

This invention relates to boring and other 10 tools in which the chuck which carries the operating bit is automatically rotated by the endwise movement of the shank into a tubular holder, the holder and shank being provided with inter-engaging members, such 15 as a screw-threaded stem attached to the holder and a nut attached to the shank and engaging said holder, whereby an endwise movement of the shank relatively to the holder is caused at the same time to rotate 20 the shank and the bit-carrying chuck attached thereto.

The invention has for its object, first, to provide a tool of this character in which the shank is adapted to be locked to the holder 25 against endwise movement, whereby first, the holder and shank may be rotated together as a hand or non-automatic tool, and secondly, the tool as a whole may be reduced to compact form by forcing the shank 30 into the holder and locking it therein against the projecting pressure of the usual spring which is provided to normally project the shank from the holder.

The invention also has for its object to 35 provide in a tool of this character an improved magazine for holding a plurality of bits, and permitting the convenient selection of any bit that may be desired for use. We use the term "bit" in this connection to indicate the acting instrument which 40 is held and rotated by the shank, it being understood that said instrument may be a boring bit or drill, a screw-driver, or any other instrument which is capable of being used with a tool of this character.

The invention consists in the improvements which we will now proceed to describe and claim.

Of the accompanying drawings, forming 50 a part of this specification,—Figure 1 represents a side elevation of a tool embodying our invention. Fig. 2 represents an eleva-

tion of the outer end of the holder. Fig. 3 represents a section on line 3—3 of Fig. 1. Fig. 4 represents a section on line 4—4 of 55 Fig. 3. Fig. 5 represents a view showing the tool in a collapsed or contracted condition, portions of the holder and shank being shown in section. Fig. 6 represents an enlargement of a portion of Fig. 3. Fig. 7 60 represents a view similar to Fig. 6, showing a different adjustment. Fig. 8 represents a sectional view of the adjustable abutment and the spring clamping ring therein, hereinafter referred to. Fig. 9 represents a section on line 9—9 of Fig. 3. Fig. 10 represents a view similar to a portion of Fig. 3, showing the magazine locking bolt retracted. Fig. 11 represents a view similar to Fig. 10, showing the magazine adjusted to receive or 70 deliver a bit.

The same reference characters indicate the same parts in all the figures.

12 represents a cylindrical shank which is provided at its outer end with a chuck 13 75 adapted to detachably engage an operating bit 14. Said shank is movable endwise into and out of a holder which, as here shown, includes a tubular inner member 15, and a tubular outer member 16, the main portion 80 of which is separated from the main portion of the inner member by an annular space which is subdivided, as hereinafter described, to form a magazine adapted to contain a plurality of operating bits 14 of different kinds, the outer member 16 having a contracted portion 17 at the inner end of the holder, which portion bears upon the inner end portion of the inner member 15, as shown in Figs. 3 and 5, the two members 90 being rigidly secured to each other in any suitable way.

18 represents a tubular stem which is attached to a head piece 19 affixed to the outer end portion of the inner member 15, said 95 stem having external screw threads 20 of abrupt pitch. To the interior of the shank 12 is affixed a nut 21 engaging the threads 18, so that an endwise movement of the shank relatively to the holder will cause a 100 rotation of the shank.

22 represents a shank-projecting spring seated at one end on an abutment at the outer end of the tubular stem 18, and at its

other end on an abutment in the chuck 13, the spring being adapted to normally project the shank from the holder, as indicated in Fig. 3.

5 When the operating bit is pressed against the work on which it acts, and the holder is moved relatively to the shank 12, so that the latter enters the shank, the engagement of the nut 21 and the screw-threaded stem 10 18 causes a rotation of the shank in one direction. When pressure on the holder is removed, the spring 21 acts to project the shank, the nut and screw-threaded stem at the same time acting to rotate the shank in 15 the opposite direction.

Our invention includes means for locking the shank to the holder, so that the tool, as a whole, may be held in a contracted condition, as shown in Fig. 5, or the shank when 20 projected to any extent desired, may be locked to the holder, so that the holder and shank may be manipulated as one part and operated as a non-automatic tool, the reciprocal action of the nut and the screw- 25 threaded stem being prevented.

The preferred means for locking the shank to the holder comprise a resilient wire clamping ring 23 which is divided at one 30 point, and is adapted to embrace the shank 12, the resilience of the ring being such that it normally expands out of engagement with the shank, and two abutments 24 and 25 carried by the holder, the ring being interposed between said abutments. The abutment 24 is fixed relatively to the holder, and is formed by the end of the contracted portion 17 of the outer member of the holder, while the abutment 25 is adjustably mounted on the holder, and is formed on an internally threaded sleeve 26 which is engaged with an external thread formed on the contracted portion 17. When the sleeve 26 is turned to the position shown in Figs. 3 and 6, the clamping ring 23 is loosely confined between the abutments, and is free to expand so that it does not bind upon the shank 12. When it is desired to lock the shank to the holder, the sleeve 26 is turned inwardly to the position shown in Figs. 5 40 and 7, this operation causing the two abutments to coöperate in compressing the clamping ring 23, and forcing it into binding engagement with the shank 12 with sufficient firmness to prevent endwise movement 55 of the shank.

It will be seen from the foregoing that when it is desired to lock the shank to the holder, the clamping ring 23 is contracted on the holder by an inward adjustment of 60 the abutment 25. This may be accomplished when the shank is in any position which it is capable of assuming, that is, either fully retracted, as shown in Fig. 5, or fully or partially projected. Provision is therefore 65 made for maintaining the tool in compact

form for storage, and for enabling the shank to be rotated by the rotation of the holder, the latter serving as a handle.

27 represents a rod which is engaged with the chuck 13, and supports the portion of 70 the spring 22 which projects from the tubular stem 18, the rod preventing the spring from buckling.

As before stated, the main portions of the members 15 and 16 of the holder are separated by an annular space, this space being subdivided to form a series of bit-containing pockets, so that the holder constitutes a magazine adapted to contain a number of bits. The subdivision of the annular space 80 is preferably effected by means of a longitudinally corrugated sheet metal sleeve 28 (Fig. 9) inserted in the annular space, the spaces between the corrugations being of sufficient width to form pockets 30 extending lengthwise of the holder, each pocket being adapted to contain a bit.

31 represents a cap which is connected by a pivot screw 32 with the head piece 19 of the holder. Said cap has an orifice 33 90 adapted to coincide with either of the pockets 30, said orifice being of sufficient size to constitute a mouth for the pocket with which it coincides, thus enabling a bit to be inserted or removed from said pocket, as 95 illustrated in Fig. 11. Said orifice is also adapted to engage a locking bolt 34 which is normally projected by a spring 35, said bolt and spring being preferably located in one of the pockets 30. When the orifice 33 is in 100 position to coincide with the pocket containing the bolt 34, the cap closes all the other pockets, and is locked by the engagement of the bolt 34 with the orifice. The bolt is provided with a stud 36 which projects through a slot 37 in the outer member 105 of the holder, and enables the bolt to be retracted to release the cap.

The external surface of the holder is preferably provided with indicating marks 38 110 which are preferably numerals, as shown in Fig. 1, said marks coinciding with the different pockets. The bits inserted in the several pockets may be designated by marks similar to the marks 38 on the exterior of 115 the holder, so that the operator is enabled to conveniently select any bit that may be desired. In Figs. 3 and 5, the bolt is shown as projected to lock the cap 31, and in Fig. 10, the bolt is shown retracted to release the 120 cap.

The chuck portion referred to comprises a body portion 13 having a socket 40 for the reception of the shank of the bit 14, and having in one side a recess in which is pivoted at 41 a jaw 42 adapted to engage a notch 43 in the bit shank. The body 13 is externally screw-threaded, and with it is engaged an internally threaded sleeve 44, one end of which is contracted to form a tapered 130

internal face 45 which is adapted when the sleeve is adjusted inwardly on the body of the chuck, to engage the outer end of the jaw 42, and force the same inwardly into engagement with the notch in the bit shank.

46 represents a spring which is connected with the body 13 and with the jaw 42, and normally swings the outer end of the jaw outwardly so that when the sleeve 44 is adjusted outwardly, the jaw automatically releases the bit and permits the latter to be withdrawn.

The jaw 42 by its projection into a notch in the bit shank, positively engages the latter when the bit is being withdrawn from the hole it has formed, separation of the jaw from the bit shank during the withdrawing movement being impossible.

We claim:

20 1. A tool of the character described, comprising a tubular holder, a tool carrying shank movable endwise in the holder, said holder and shank having interengaged members which cause the rotation of the shank when it is moved endwise, a spring which normally projects the shank from the holder, and means for locking the shank at any point in its range of projection to prevent rotation and endwise movement thereof.

25 2. A tool of the character described, com-

prising a tubular holder, a tool carrying shank movable endwise in the holder, said holder and shank having interengaged members which cause the rotation of the shank when it is moved endwise, a spring 35 which normally projects the shank from the holder, and a shank locking device carried by the holder and constructed to engage the shank at any point in its range of projection to prevent rotation and endwise movement 40 thereof.

3. A tool of the character described, comprising a tubular holder, a tool carrying shank movable endwise in the holder, said holder and shank having interengaged 45 members which cause the rotation of the shank when it is moved endwise, a spring which normally projects the shank from the holder, a clamp constructed to engage said shank at any point in its range of projection 50 to prevent rotation and endwise movement thereof, and means carried by said holder for controlling the operation of said clamp.

In testimony whereof we have affixed our signatures, in presence of two witnesses.

JOHN A. LELAND.

WILLIAM G. STEBBINS.
